NECKTIE DISPLAY STAND

Filed Feb. 18, 1929

UNITED STATES PATENT OFFICE

CHARLES W. JOHAM, OF LOS ANGELES, CALIFORNIA, ASSIGNOR TO STERN, JOHAM AND GROSSMAN, INC., A CORPORATION OF CALIFORNIA

NECKTIE-DISPLAY STAND

Application filed February 18, 1929. Serial No. 340,729.

This invention relates to store display fixtures and especially to a device in the form of a cover for what is generally, and well known, in the trade as a "collar and tie top."

5 It has been an ancient practice to utilize a stand having a circular top, with a bottom ledge, as a holder on which a dress collar with an applied tie is mounted; the inner band of the collar resting on the bottom ledge 10 of the top.

It will be seen that this requires the use of a fresh, clean or new collar when it is desired to display a tie, as the special on sale. The collar becomes soiled and must be disposed of at a loss.

In the present invention one object is to utilize the usual "top" of the display stand without change and to provide an attachment in the form of a cover which will telescope 20 over the usual "top" after the tie has been applied and drawn up tight on the circular face of the top; which cover for the top will simulate a collar, and which is wholly free or detached as to the top so that the tie 25 can be perfectly draped and tied on the top before the cover or imitation collar is applied.

Other objects, advantages and features of construction, and a method of manufacture of the imitation collar will be made manifest 30 in the ensuing description of the herewith illustrative embodiment; it being understood that modifications, variations and adaptations may be resorted to within the spirit, scope and principle of the invention as it is hereafter more directly claimed.

Figure 1 is a perspective of the applied cover.

Figure 2 is a central section of the applied cover.

40 A well known show fixture for haberdashers' use consists of a standard 2 on the top of which is mounted a circular "top" 3 of a depth to receive a linen collar on which a tie has been draped, the collar resting on the bottom ledge 3a.

In Fig. 2 this "top" is shown as of spun sheet metal.

An advantage sought by the present invention is to dispense with the use of a real collar and to derive the full display of a

tie T after this has been tied directly on the circular face of the "top" 3.

To that purpose I provide an appliance consisting of a cover 5 having a downwardly extending imitation collar 6 of such size as to snugly fit about the ledge 3a of the top 3 and cover the applied band B of the draped tie T.

A feature of the invention is the realistic front, flared points 7 spread to form a throat 60 opening for the knot of the tie T, looped up tight on the top 3.

It will be seen that the cover 5 is in itself a complete article of manufacture and is saleable as an appliance to be mounted on the 65 old, well-known "collar and tie top" already forming a part of the fixture equipment of a haberdasher store.

What is claimed is:

A necktie display appliance comprising, 70 in combination, a pair of separable elements one of which consists of a form about which a tie is adapted to be looped and knotted in display position, and the other element comprising a cover adapted to be applied to the 75 form element after the tie has been arranged and which includes a down-turned perimetric interrupted flange to telescope over the band of the tie on the form element.
